GOLF TEE

Harry N. Andreasen, Sr., Chicago, Ill.

Application January 22, 1947, Serial No. 723,509

1 Claim. (Cl. 273—33)

1

This invention relates to golf tees of the character used to support a golf ball above the ground.

Many of the people who play the game of golf consistently, desire to tee the ball substantially the same distance above the ground for each drive, and it is a primary object of my invention to enable this to be accomplished by affording a novel unitary tee which has such characteristics that it may be readily used, either on hard or soft ground, to support a ball in the proper manner and at the same desired height.

Another object of my invention is to afford a novel golf tee having two elongated projecting members, either of which may be used to support the tee on the ground and the other of which may then act as a pointer to indicate the direction the ball should follow when driven therefrom.

A further object of my invention is to so construct a golf tee that it is relatively small and compact so that it may be readily carried on the person of the golfer, and also has sufficient innate strength and rigidity to effectively withstand the normal abuse to which a golf tee is subjected.

Another object of my invention is to construct a golf tee in such a manner that if, in the execution of his swing, a golfer tops the tee, the tee will tend to stick into the ground at his feet rather than slide or roll away as has been the tendency of tees heretofore known to the art.

Yet another object of my invention is to afford a novel golf tee that may be easily and economically manufactured commercially.

Other and further objects of the present invention will be apparent from the following description and claims and are illustrated in the accompanying drawings which, by way of illustration, show a preferred embodiment and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claims.

In the drawings:

Fig. 1 is an elevational view of a golf tee embodying my invention as it would appear when used in soft ground;

Fig. 2 is an elevational view of a golf tee similar to the view shown in Fig. 1 but showing the tee as it would appear when used in hard ground;

2

Fig. 3 is a top plan view of the tee shown in Fig. 1;

Fig. 4 is a sectional view taken substantially along the line 4—4 in Fig. 3; and

Fig. 5 is a sectional view taken substantially along the line 5—5 in Fig. 1.

The tee shown in the accompanying drawing may be made of any suitable material such as, for example, wood or a synthetic resinous plastic material such as a phenolic condensation product and of which the acrylic acid resin known as "Lucite" is a specific example, and comprises two legs 11 and 12 which are joined together at one end to form an enlarged body member 14, and which extend substantially at right angles to each other. The enlarged body member 14 comprises a head 14a and a web 14b which, together form a strong reinforced connection between the two legs 11 and 12.

Both of the legs 11 and 12 are formed with a relatively large cross section at their joined ends and taper gradually therefrom to a relatively sharp point at their free ends. The leg 12 is preferably made somewhat longer than the leg 11 for reasons which will be discussed in greater detail hereinafter.

Two indentations or sockets 16 and 17, having substantially circular-shaped rims 19 and 20, respectively, are formed in the body member 14 and are in substantial axial alignment with the legs 11 and 12, respectively. The indentations 16 and 17 are of such size that a standard golf ball will firmly rest on the rims 19 and 20 thereof when the tee is placed in such a position that the rim 19 or 20 on which the ball is to rest is in a substantially upward facing, horizontal position.

In using my novel tee either the leg 11 or the leg 12 is stuck substantially vertically into the ground with the other one of the two legs pointing toward the green toward which the golfer is to drive. A ball, such as the ball indicated generally at A in the drawings, may then be placed on the rim of either indentation 16 or 17 depending upon which of the legs 11 or 12 is stuck into the ground. The legs 11 and 12 are each of such length that whichever one is pointed toward the green in the aforesaid manner the outer end thereof is readily visible to the golfer as he addresses the ball, and serves as a pointer indicating the direction of flight the ball must follow to alight on or adjacent the green. Thus it will be seen that, when using my novel tee, it is unnecessary for the golfer, in addressing the ball, to glance toward the green for the purpose of properly adjusting his stance and properly posi-

tioning the head of his club, it merely being necessary for him to look at the ball and the leg of the tee which he has previously adjusted to indicate the direction to the green, and, therefore, he may concentrate on keeping his eye on the ball.

It will be noted that my novel tee is so constructed that one leg 12 is considerably longer than the other leg 11, so that when using my tee on soft ground, where it is desirable for more of the tee to have purchase in the ground so as to adequately support the ball. A thereon, the longer leg 12 may be struck into the ground, and when using my tee on hard or firmer ground, where it is unnecessary for so much of the tee to have purchase in the ground, the shorter leg 11 may be stuck into the ground. Thus it will be seen that by making the one leg 12 longer than the other leg 11, I have provided a tee wherein the ball may be adequately and properly supported at the same desirable height above the ground whether the ground be hard or soft.

It will be noted that when my tee is in use and the golf ball is driven therefrom in the direction indicated by the pointer, in such a manner that the club head not only strikes the ball but also tops the tee, the impact will tend to drive the direction indicating pointer into the ground so as to retard movement of the tee and thereby prevent loss thereof.

Thus, it is clear from the drawings that my golf tee comprises a rigid one piece body including a head having rounded sides, spaced right-angularly disposed ends and a rounded top between and spacing the ends from each other. The ball-receiving sockets 16 and 17 are tapering and formed entirely within the area of the head. These sockets terminate in apexes which are in spaced relation to one another within the head, the solid area of the head between the sockets forming a strong reinforcing connection therebetween. The web 14b having smooth exterior sides and of diminishing cross sectional area is integral with the head and depends therefrom. The rounded sides of the head project beyond the sides of the web and the right-angularly disposed tapering legs 11 and 12 are integral with and extend from the web in alignment with the sockets. The transverse cross sectional area of both legs diminishes toward their outer extremities in continuation of the diminishing transverse cross sectional area of the web. It is clearly seen, therefore, that the solid area of the head between the sockets and the web that is integral with the head and the respective legs, respectively provide a strong reinforcing connection between the sockets and between the head and the respective legs.

From the foregoing it will be seen that I have provided a novel tee which may be readily used by a golfer to support a golf ball when he is making a drive, is structurally strong, and has certain novel structural features that will be of considerable assistance to a golfer in properly executing a stroke, and will tend to improve his game.

Furthermore it will be noted that my novel tee is adapted to function well in either hard or soft ground, has certain novel features which tend to protect it from being lost, is easy to use, and may be readily manufactured commercially.

Thus, while I have illustrated and described the preferred embodiment of my invention, it is to be understood that this is capable of variation and modification and I therefore do not wish to be limited to the precise details set forth, but desire to avail myself of such changes and alterations as fall within the purview of the following claim:

I claim:

A golf tee comprising a rigid one piece body including a head having rounded sides, spaced right-angularly disposed ends and a rounded top between and spacing the ends from each other, the said ends having recessed tapering sockets therein, the area of said sockets being entirely within the head, said sockets terminating in apexes which are in spaced relation to one another within the head, a web having smooth exterior sides and of diminishing transverse cross sectional area and of less transverse cross sectional area than the transverse cross sectional area of the head, integral with the head and depending therefrom, the sides of the head projecting beyond the sides of the web, and right-angularly disposed tapering legs integral with and extending from the said web in alignment with the sockets; one of said legs being longer than the other and the transverse cross sectional area of both legs diminishing toward their outer extremities in continuation of the diminishing transverse cross sectional area of the web, the solid area of the head between the sockets, and the said web integral with the head and the respective legs, respectively providing a strong reinforcing connection between the sockets and between the head and the respective legs.
